Primary Examiner — Ian Simmons*Assistant Examiner* — Eleni Aldridge(74) Attorney, Agent, or Firm — Wells St. John P.S.(57) CLAIM

I claim the ornamental design for a coat, as shown and described.

DESCRIPTION

FIG. 1 is a front view of a coat showing my new design; and, FIG. 2 is a rear view thereof.

The broken line showing of stitching is included for the purpose of illustrating portions of the article that forms a part of the claimed design.

1 Claim, 2 Drawing Sheets(56)
